Primary Examiner—Ted Shooman*Assistant Examiner*—Daniel Bui(74) *Attorney, Agent, or Firm*—Dara M. Kendall; Tara M. Rosnell; Steven W. Miller**CLAIM**

The ornamental design for a sprayer cartridge, as shown and described.

DESCRIPTION

FIG. 1 is a perspective view of the sprayer cartridge design; FIG. 2 is a left side elevational view thereof; the right side elevational view being a mirror image;

FIG. 3 is a front elevational view thereof;

FIG. 4 is a rear elevational view thereof;

FIG. 5 is a top view thereof; and,

FIG. 6 is a bottom view thereof.

The broken line showing the environment is for illustrative purposes only and forms no part of the claimed design.
